Primary Examiner — Thomas Johannes*Assistant Examiner* — Jasmine Mlinarcik(74) Attorney, Agent, or Firm — Rick B. Yeager(57) CLAIM

The ornamental design for a soccer themed beanie, as shown and described.

DESCRIPTION

FIG. 1 is a front elevation view of a soccer themed beanie shown in a position of use.

FIG. 2 is a rear elevation view of the soccer themed beanie of FIG. 1.

FIG. 3 is a first side perspective view of the soccer themed beanie of FIG. 1; and,

FIG. 4 is a second side perspective view of the soccer themed beanie of FIG. 1.

The human figure drawn in broken lines is environmental structure to illustrate how the soccer themed beanie is in a position of use and forms no part of the claimed design. The numerals “13”, the flag, and the logo outlined by broken lines depict portions of the soccer themed beanie that form no part of the claimed design.

1 Claim, 2 Drawing Sheets*FIG. 1*
